DESIGN FOR A TABLE

Chauncey E. Waltman, Chicago, Ill., assignor to Sandel Manufacturing Co., Chicago, Ill., a corporation of Illinois

Application October 3, 1942, Serial No. 108,413

Term of patent 7 years

To all whom it may concern:

Be it known that I, Chauncey E. Waltman, a citizen of the United States and resident of Chicago, in the county of Cook and State of Illinois, have invented a new, original, and ornamental Design for a Table, of which the following is a specification, reference being had to the accompanying drawing, forming a part thereof.

Fig. 2 is a fragmentary sectional view, taken along the line 2--2 of Fig. 1, for the purpose of more clearly illustrating the contour of the article.

The two sides of the table not shown are the same as the two sides shown in Figure 1.

I claim:

The ornamental design for a table, substantially as shown and described.

CHAUNCEY E. WALTMAN.
